DISK HOLDING DEVICE

Ivar E. Sjøvæland, St. Paul, Minn.

Application July 8, 1941, Serial No. 401,508

12 Claims. (Cl. 32—59)

My invention relates to an improvement in a disk holding device wherein it is desired to provide a device for facilitating the changing of sand paper disks, and the like, used in dentistry.

For many purposes in dentistry various types and classes of abrasive disks are used. These disks are secured to the end of the hand piece or contra angle and are rotated by the dental engine in the usual way for grinding and polishing purposes. It has been common practice to insert a screw or bolt through a central opening in the disk and to screw this bolt into a suitable disk support by rotation of the support by the dental engine. Other types of disk holding means have also been provided, but the bolt has been most commonly used because of its simplicity.

It is the object of the present invention to provide a disk holding device which will support an abrasive disk, or the like, and which will permit changing or replacing of the disks in an extremely simple and effective manner. In applying the disk, it is only necessary to place the disk against the end of the holder and to rotate the dental engine, the disk threading its way onto the holder when the disk is in place. It is only necessary to grasp a portion of the holder, whereupon the disk is firmly secured in place.

It is a feature of the present invention to provide a disk holding device which embodies the use of a spiral spring upon which the disk is threaded. When the disk has been threaded into operative position, the center of the spiral spring is pulled into alignment or substantial alignment with the outer convolutions of the spring, making a flat spiral, rather than a conical-shaped spring. When in this flat relation, the spring acts to hold the disk firmly in place and to prevent rotation of the disk with respect to the holder.

A feature of my invention lies in the simplicity of the disk holder. The complete holder comprises nothing more than a spiral conical-shaped spring, a shank for supporting the spring and a nut threadable on the supporting shank. Through the use of these three elements a disk holder may be formed which will permit extremely fast changing of the disks.

A further feature of my invention lies in the provision of a spiral spring which is substantially conical-shaped and which is provided with a central connecting member by means of which the center of the spring may be pulled downwardly until all of the convolutions of the spring are in substantially the same plane. This central connecting member may be either a portion of one end of the spring or may be a separate member to which the upper end of the spring may be attached.

A feature of my invention resides in the fact that disks of the most inexpensive type may be

securely held by my disk holder and that no special disks are required for use in conjunction with the holder. As a result, the disks which are designed for use with the most common type of disk holding means may be used with the present construction and that there is no necessity of changing the style of disks which must be used.

These and other objects and novel features of my invention will be more clearly and fully set forth in the following specification and claims.

In the drawings forming a part of my specification:

Figure 1 is a perspective view of the end of a hand set showing my disk holder holding the disk in place thereupon.

Figure 2 is a cross-sectional view through the disk holder illustrating the construction thereof, in enlarged form.

Figure 3 is an outside elevation view of the disk holding device in greatly enlarged form.

Figure 4 is a view similar to Figure 2, showing the disk holder in position to support a disk.

Figure 5 is a cross-sectional view similar to Figure 2 illustrating a slightly modified form of construction.

Figure 6 is a sectional view similar to Figure 4 showing the modified form of construction in disk holding position.

Figure 7 is a greatly enlarged perspective view of the spring used in conjunction with the holder.

Figure 8 is a sectional view similar to Figure 2 showing another modified form of disk holder construction.

Figure 9 is a sectional view similar to Figure 8, but showing the disk holder in disk holding position.

Figure 10 is a sectional view through the nut or threaded sleeve within which the disk holder operates.

Figure 11 is a view of the shank of the holder in greatly enlarged form.

Figure 12 is a perspective view of the spring used in conjunction with the disk holder of views 8 and 9.

The disk holder A illustrated in Figures 1 through 4 of the drawings comprises a hollow shank 10 having external threads 11 thereupon at one end thereof. The shank 10 is threaded into a nut or sleeve 12 which is formed in two parts.

The major part 13 of the nut or sleeve 12 is internally threaded to engage the external threads of the shank 10. The tip portion 14 is provided with a hollow threaded sleeve 15 integral therewith which also threads into the internal threads of the major portion 13 of the nut or sleeve 12. An opening or passageway 16 extends through the sleeve or nipple 15 and thorough the entire tip portion 14, this bore 16 being in alignment with the bore 17 of the shank 10.

A spiral conically-shaped spring 18 projects be-

yond the tip 14 of the sleeve 12. This spring 19 has a relatively large spring convolution at the base of the spring and has successively smaller diameter convolutions as the spring progresses toward its upper tip end 20. The tip end 20 is connected by a connecting member 21 to the shank 10. In the construction illustrated the connecting member 21 extends from the tip end 20 through the aligned bores 16 and 17 and is bent over the end of the shank 10, as illustrated at 22, fitting into a groove in the shank 10 and being securely soldered or welded in place. The large diameter end 23 of the spring 19 is connected by a connecting wire 24 which extends through the bore 16, together with the connecting member 21 and is anchored within the tip 14. The anchor may be in the form of a loop 25 formed of the spring wire and resting freely against the end of the projecting sleeve or nipple 15. It is essential that the anchoring loop 25 rotate with respect to the nipple in operation of the device.

In operating the disk holder, the disk B is placed against the tip end 20 of the holder so that the central opening 26 therein accommodates the tip end 20. The entire tip end is rotated by the dental engine, the shank 10 being supported in a suitable chuck or other holding device. Rotation of the holder A, while the disk B is held stationary causes the spring wire 10 to thread itself into the opening 26 of the disk B until the disk rests against the end surface 27 of the sleeve 12.

In order to clamp the disk in place, the sleeve 12 is next held from rotation while the shank 10 continued its rotation. This causes the shank 10 to be threaded outwardly in the sleeve 12 and causes the connecting member 21 to be drawn toward the surface 27 of the sleeve. This forces the spring 19 to assume a flat position upon the surface of the disk. The convolution of the spring is positioned in a substantially flat plane. When in this position, the disk B may be used for its prescribed purpose.

When it is desired to change disks, it is only necessary to reverse the direction of rotation of the dental engine and to engage the sleeve 12 with the fingers for a short period of time until the spring 19 assumes its natural position as illustrated in Figure 3 of the drawings. The disk B is then engaged with the fingers and the continued rotation of the holder causes the disk to be threaded off of the spring 19.

It will be noted that as the spring 19 is formed of relatively thin spring wire the hole 26 does not increase substantially in size by insertion of the spring. As the disk moves to place, the spring 19 flexes toward the central connecting member 21, thus preventing the tearing of the disk.

In Figures 5 and 6 of the drawings, I disclose a slightly different form of construction of disk holder. This construction is very similar to that previously described, but some differences exist. In the construction illustrated in Figures 5 and 6, a shank 29 is provided which is hollow and has an axial bore 30 extending therethrough. The shank 29 is externally threaded at 31. A nut or sleeve 32 is internally threaded to accommodate the shank 29. The threads preferably do not extend entirely through the nut or sleeve 32, in order to limit pivotal movement of the shank in one direction. A smooth non-threaded portion 33 is shown within the nut or sleeve 32 in the upper extremity thereof. The shank 29

is preferably provided with a non-threaded upper extremity 34 which extends through the unthreaded portion 33 of the sleeve 32.

A spiral conically-shaped spring 35 is secured 5 to overlie the end surface 36 of the sleeve 32. This spring 35 has at its lower end 37, relatively large convolutions which are coiled successively smaller in diameter until they reach the top peak end 39. This top peak end 39 is designed 10 to extend through the central opening 26 of the disk B and by holding the disk while the spring 35 rotates in one direction, the disk may be threaded onto the spring until it rests on the surface 36. Rotation of the spring 35 in the opposite direction, while the disk B is held stationary, causes this disk to be unthreaded from the spring 35.

In order to insure the centering of the disk B with respect to the holder B, the aperture 26 20 is adapted to permit the unthreaded end 34 of the shank 29 to extend therethrough. Thus, when the disk B is in place in the dotted outline position of Figure 5 of the drawings, this disk is held centered by the unthreaded end 34 of the shank 29.

In order to clamp the disk B, the nut or sleeve 32 is held stationary for a short period of time while the shank 29 continues rotation, the shank 30 threading its way partially out of the sleeve 32 and pulling the center of the spring 35 downwardly until the various convolutions of the spring are in the same plane. The peak end 39 of the spring 35 is connected by a connecting member 40 to the shank 29, the end of the connecting member 40 being illustrated at 41, as bent over the end of the shank 29 and extending in a groove therein. This end 41 is preferably soldered or welded in place. The large diameter end 37 of the spring 35 is secured to a connecting member 42 which extends through the bore 30 of the shank 29 and projects beyond the end of the shank. An anchoring tip 43 is secured to the end of the connecting member 42 and a spring 44 encircles the connecting member 42 between the anchoring end 43 and the extreme end of the shank 29.

In Figures 8 and 9 of the drawings, I disclose a holder D which differs in some respects from the previously described holders. The disk holder D includes a shank 45 which is provided with a threaded portion 46, an unthreaded portion 47, and a projecting tip portion 49. A shoulder 50 may, if desired, encircle the shank 45 between the lower portion of the shank and the threaded portion 46 to limit rotation of the shank in one direction.

A nut or threaded sleeve 51 is internally threaded at 52 to accommodate the threads 46 of the shank 45. An upper unthreaded portion 53 is provided to accommodate the unthreaded portion 47 of the shank 45. The unthreaded portion 53 is connected by a relatively small diameter passage 54 or through the sleeve or ring 58 threaded into the sleeve 51 providing a shoulder 55 at the end of the unthreaded portion 53 between this portion and the smaller diameter passage 54. The tip end 49 of the shank 45 is designed to extend through this small diameter passage 54 with plenty of play.

Upon the end surface 56 of the nut or sleeve 51, I provide a spring 57. The large diameter portion 59 of the spring 57 rests upon the surface 56 and the convolutions of the spring are of successively smaller diameter toward the upper spring end 60. This upper spring end 60 is

designed to extend through a tiny opening 61 in the tip end 49 of the shank 45. The large diameter end 59 is connected by a short connecting portion 62 to a spring convolution 63 which is designed to engage inwardly of the shoulder 55.

This construction is provided in order to produce a disk holder in which the springs may be readily changed. It is obvious with this construction that if the spring 57 should break, it may be removed by withdrawing the tip end 60 from engagement with the hole 61 and by withdrawing the spring convolutions or loop 63 from engagement with the shoulder 55. The loop or convolution 63 may be threaded through the small diameter passage 54 of the bushing or ring 58, and this ring 58 screwed into place. When the convolution 63 is in place, the shank 45 may be inserted and the tip end 60 secured in place.

In accordance with the patent statutes, I have described the principles of construction and operation of my disk holder, and while I have endeavored to set forth the best embodiments thereof, I desire to have it understood that these are only illustrative of a means of carrying out my invention and that obvious changes may be made within the scope of the following claims without departing from the spirit of my invention.

I claim:

1. A disk holder comprising a threaded shank adapted to be supported in a dental hand piece, a substantially conically shaped spiral spring projecting from said shank, and nut means threadably engaged on said shank, said spring designed to threadably engage into an abrasive disk, and said nut operable on said shaft to compress said spring into a substantially flat plane to clamp said disk against said nut.

2. A disk holder comprising a substantially conical spiral spring, means for rotatably supporting said spring to thread or unthread itself into or out of a disk, and means for compressing the convolutions of said spring into a substantially flat plane to clamp said disk.

3. A clamping device in combination with an element to be clamped having an opening therethrough, the clamping device comprising a substantially conical spring designed to threadably engage into or out of said opening, and means for compressing said spring into a substantially flat plane to clamp said element.

4. A clamping device in combination with an element to be clamped having an opening therethrough, the clamping device comprising a substantially conical spiral spring designed to threadably extend through the opening in said element, and means secured to the tip end of said spiral spring and compressing said spring to clamp said element.

5. A clamping device in combination with an element to be clamped, the clamping device comprising a spiral substantially conically shaped spring, shoulder means against which said spring engages, said spring designed to threadably engage through the opening in said element until said element rests against said shoulder, and means compressing said spring to clamp said element.

6. A clamping device in combination with an element to be clamped having an opening therethrough, the clamping device comprising a spiral substantially conical spring, shoulder means against which said spring engages, said spring designed to threadably engage through the opening in said element until said element rests upon

said shoulder, and means secured to the apex of said spring to draw the convolutions thereof into a substantially flat plane to clamp said element against said shoulder.

5 7. A disk holder for use with abrasive disks having a central aperture therethrough, the holder including a sleeve, a substantially conical spiral spring, means on the large diameter end of said spring holding said spring rotatable with respect to said sleeve and in proximity thereto, and means secured to the small diameter end of said spring extending into said sleeve, and means for exerting longitudinal pull on said connecting means to compress said spring.

10 8. A disk holder comprising a sleeve, a conical spiral spring, means securing one end of said spring rotatable with respect to said sleeve and in proximity therewith, connecting means secured to the other end of said spring and extending through said spring and into said sleeve, and means secured to said connecting means to exert a longitudinal pull thereupon to compress said spring.

15 9. A disk holder for use with abrasive disks, 25 said holder including a sleeve, a stud threadably engaging within said sleeve, a spiral conical spring secured at its large diameter end to said sleeve to rotate with respect thereto, the large diameter end of the spring being held in proximity to said sleeve, a connecting means secured to the small diameter end of said sleeve and to said stud whereby longitudinal movement of said stud with respect to said sleeve may act to compress said spring.

30 10. A disk holder for use in conjunction with disks having a central opening therethrough comprising a sleeve, a hollow nipple extending into said sleeve, a conical spiral spring threadably engaging said disk so that said disk may be threaded against the end of said nipple, means anchoring the large diameter end of said spring within said nipple to rotate with respect thereto, a stud threadably engaging into said sleeve and connecting means secured to the small diameter 45 end of said spring and to said stud to compress said spring against said disk.

35 11. A disk holder for use with disks having an aperture therethrough comprising an internally threaded sleeve, a stud threadably engaging said sleeve and having an end projecting beyond an end of said sleeve, a conical spiral spring secured at its large diameter end to a connecting means extended through said stud from said one end thereof, and projecting beyond the other end thereof, a spring encircling said connecting means between the end thereof and said other end of said stud, and connecting means secured to said stud and to said small diameter end of said spring, said spring being threadably engaged in the opening of the disk until said disk encircles said one end of said stud, longitudinal movement of said stud acting to clamp said spring against said disk.

40 12. A disk holder for dental disks having an opening therethrough, said holder comprising a sleeve internally threaded, a stud engageable with said threads to move longitudinally of said sleeve, an end on said stud projecting through said sleeve and beyond one end thereof, a conical spiral spring secured at its small diameter end to said end on said stud, and means rotatably securing the large diameter end of said spring to said sleeve.
